CLAIM

The ornamental design for a member of battery unit for vibration sensor as shown and described.

DESCRIPTION

FIG. 1 is a front and left perspective view of a member of battery unit for vibration sensor, showing our new design. FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is a cross-sectional view taken along the line 8-8 in FIG. 4.

FIG. 9 is a cross-sectional view taken along the line 9-9 in FIG. 2; and,

FIG. 10 is a reference view showing use thereof.

The broken lines shown in the drawings illustrate portions of the member of battery unit for vibration sensor that form no part of the claimed design.
